UNITED STATES PATENT OFFICE.

ANTONE T. HOHLE, OF MINNEAPOLIS, MINNESOTA.

TONGUE-DEPRESSOR.

1,274,547.

Specification of Letters Patent.

Patented Aug. 6, 1918.

Application filed November 11, 1916. Serial No. 130,768.

To all whom it may concern:

Be it known that I, ANTONE T. HOHLE, a citizen of the United States, residing at Minneapolis, county of Hennepin, and State 5 of Minnesota, have invented new and useful Improvements in Tongue-Depressors, of which the following is a specification.

One object of my invention is to provide a handle having means thereon for detachably carrying tongue splints.

Another object of my invention is to provide a flash light serving as an instrument handle with means thereon for carrying with a detachable connection a common 15 type of tongue splint.

Another object of my invention is to provide in an instrument of the kind described means for receiving and holding with a detachable connection two different sizes of 20 tongue splints.

With these and incidental objects in view, the invention consists of certain novel features of construction and combination of parts, the essential elements of which are 25 hereinafter described with reference to the drawing which accompanies and forms a part of this specification.

In the drawing, Figure 1 is an isometric view of my improved tongue depressor. 30 Fig. 2 is an end view showing one method of receiving two different sizes of tongue splints, and Fig. 3 is my preferred construction of the instrument adapted to receive two sizes of tongue splints.

35 A flash light 1 of ordinary construction serves as the handle of the instrument and carries the ordinary electric bulb 2 at the farther end thereof with the battery concealed in the handle, and the switch 3 serves 40 to close or open the battery circuit through the lamp in any suitable manner.

Carried by the forward end of the barrel of the flash light is a receiving socket 4 having a substantially rectangular cross section 45 with one side cut away to give flexibility to the socket.

This socket is adapted to receive between the sides 5 a tongue splint of the size used for adults and of the common type 50 made of wood and sufficient frictional pressure is exerted by the socket to firmly retain the splint in position.

These wooden splints are customarily carried by physicians when making calls as they can be used and thrown away, where 55 the ordinary style of tongue depressor having a permanent tongue piece must, of course, be sterilized each time it is used.

In my preferred construction, as shown in Fig. 3, I have the channel so shaped that a 60 tongue splint 6 of the size for adults may be carried in one portion of the socket, or a tongue splint 7 of the children's size may be carried in the outer portion of the socket, either socket being adapted to hold by frictional tension the tongue splint for which it is designed.

In the alternate construction shown in Fig. 2, I furnish with the socket 4 a second socket 8 adapted to slide in and be held by 70 the socket 4 as would the adult size of tongue splint, and this removable socket is of the proper size to receive and hold the children size of tongue splint.

Either of the constructions shown allow 75 the use of an antiseptic and inexpensive form of tongue splint that can be used once and thrown away and thus obviate the necessity of sterilizing the instrument when it is used away from the physician's office. 80

While I have described my invention and illustrated it in one particular design, I do not wish it understood that I limit myself to this construction as it is evident that the application of my invention may be varied in many ways within the scope of the 85 following claims.

Claims:

1. In a tongue depressor, the combination of an instrument handle and a double socket, 90 one portion of which is designed to hold by frictional tension a tongue splint of a certain size and the other portion of which is designed to hold by similar means a tongue splint of small size. 95

2. In a tongue depressor, the combination of an instrument handle, a receiving socket carried thereby having double gripping means, one of which is adapted to grip and hold a tongue splint of one size and the 100 other of which is adapted to grip and hold a tongue splint of a different size.

ANTONE T. HOHLE.
